DESIGN FOR A GLOVE

Julius A. Higier, Gloversville, N. Y.

Application December 8, 1937, Serial No. 73,432

Term of patent 3½ years

To all whom it may concern:

Be it known that I, Julius A. Higier, a citizen of the United States of America, residing in Gloversville, in the county of Fulton and State of New York, have invented a new, original, and ornamental Design for a Glove, of which the following is a specification, reference being had to the accompanying drawing, forming part thereof, wherein,

I claim:

The ornamental design for a glove, substantially as shown. JULIUS A. HIGIER.
